(57) **CLAIM**

The ornamental design for a height adjustable mechanic's chair, as shown and described.

DESCRIPTION

FIG. 1 is a top, right side, front perspective view of a height adjustable mechanic's chair showing our new design;

FIG. 2 is a front elevational view thereof;

FIG. 3 is a rear elevational view thereof;

FIG. 4 is a left side elevational view thereof, the right side elevational view being a mirror image of FIG. 4;

FIG. 5 is a top plan view thereof; and,

FIG. 6 is a bottom plan view thereof.

The broken line portions of the height adjustable mechanic's chair are for illustration purposes only and form no part of the claimed design.
